(57) **CLAIM**

What is claimed is the ornamental design for a user interface for a scheduler, as shown and described.

DESCRIPTION

FIG. 1 is a front view of a page of a computer display with a user interface for a scheduler showing a first image;

FIG. 2 is a front view of a second image thereof;

FIG. 3 is a front view of a third image thereof;

FIG. 4 is a front view of a fourth image thereof; and,

FIG. 5 is a front view of a fifth image thereof.

The appearance of the transitional image sequentially transitions between the images shown in FIGS. 1-5.

The process or period in which one image transitions to another image and the broken-lines showing images and text within the user interface form no part of the design claimed.
